Inventor:
Jacob Kaufmann,
By Jas. C. Nobenwith
Attorney.

UNITED STATES PATENT OFFICE.

JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE FRAME.

Application filed February 17, 1923. Serial No. 619,610.

To all whom it may concern:

Be it known that I, JACOB KAUFMANN, a citizen of the United States, residing at Elkins Park, in the county of Montgomery 5 and State of Pennsylvania, have invented certain new and useful Improvements in Heddle Frames, of which the following is a specification.

My invention relates to heddle frames for 10 looms, and it has particular relation to means for supporting the heddle bars intermediate their ends.

The principal object of my invention is to provide improved means for supporting 15 the heddle bars intermediate their ends which will securely support said bars against undesirable motion, but which, however, will permit the bars to be conveniently mounted in and dismounted from the frame 20 when desired.

My present invention contemplates an improved device for supporting the heddle bars intermediate their ends which, while permitting the bars to be more easily and 25 conveniently inserted and removed than heretofore, is so constructed and arranged as to reduce to a minimum the likelihood of the supporting device becoming disarranged while the heddle frame is in use and there- 30 by fouling with the adjacent frames in the loom, thus minimizing the possibility of damage which might be occasioned by such disarrangement.

The nature and characteristic features of 35 my present invention will be more readily understood from the following description, taken in connection with the accompanying drawings forming part hereof, in which:

Figure 1 is an elevational view of a heddle 40 frame provided with heddle bar supporting devices embodying the main features of my present invention;

Fig. 2 is a fragmentary sectional view, enlarged, taken approximately on the line 45 2—2 of Fig. 1, the parts being shown in the normal positions assumed while supporting the heddle bar in the frame;

Fig. 3 is a similar view, but with the 50 parts in the open position for the purpose of removing or mounting the heddle bar therein; and

Fig. 4 is a fragmentary elevation enlarged, showing a novel form of supporting

device mounted on the heddle frame with the heddle supporting bar in operative relation thereto.

Referring to the drawings, the heddle frame there shown consists of the top and bottom bars 6 connected at their ends by means of the side strips 7. Extending from 60 end to end of the heddle frame, and arranged near the top and bottom bars 6 in the usual manner, are the heddle bars 8, upon which the heddles 9 are mounted.

The inner edge of each of the heddle 65 frame bars 6 is preferably recessed, as at 10, wherever it is desired to support the heddle bars intermediate their ends. In this recess 10 is mounted the base portion 11 of a bracket member constituting a part of 70 the supporting device. The bracket member also has a portion 12 extending at right angles to the base portion 11, and consequently at right angles to the longitudinal 75 extension of the heddle bar 8. In the extending portion 12 of the bracket member there is provided a recess 13 open at one side, as clearly shown in Fig. 3 of the drawings, for the reception of the heddle bar 8.

A plate member 14 is pivoted to the extension 12 of the bracket member, preferably by means of a rivet 15, this pivotal connection being located at a point beyond the location of the recess 13. The pivoted plate member 14 is also provided with a 85 recess 16, open on the side opposite that upon which the recess 13 of the extension 12 of the bracket member is open, the arrangement being such that when the plate member 90 is in its closed position, as shown in Fig. 2 of the drawings, the heddle supporting bar will be limited against sidewise movement, as well as up and down movement, in the coacting recesses 13 and 16.

The end of the plate member 14, remote 95 from the pivot 15, is also recessed as at 17, as clearly shown in Fig. 3 of the drawings. A plate spring 18 is secured to the base portion 11 of the bracket member by means of the screws 19, which also serve to 100 secure the base portion 11 of the bracket member in position. The free end 20 of the plate spring 18 extends through an aperture 21 in the bracket member, located at the juncture of the extending portion 12 105 and the base portion 11 of said bracket mem-

ber. The plate spring is adapted, when the parts are in their normal operative position, as illustrated in Fig. 2 of the drawings, to act as a latch by engaging the recess 17 of the plate member 14 and thereby securely locking the same in the closed position for supporting the heddle bar 8. It will be noted, however, that the free end 20 of said leaf spring 18 may be manually operated to free the same from its engagement with the recess 17, and thereby permit the member 14 to be swung to the open position when desired. The end of the plate member 14 has a curved inclined portion 22 adjacent the recess 17, so that the plate member may be snapped into the closed position, without necessitating the raising of the end of the leaf spring 20, when it is desired to close the plate member 14 over the heddle bar 8.

The operation of the device will now be quite apparent. The supporting devices being mounted in the heddle frame, as hereinbefore set forth, and it being desirable to mount a heddle supporting bar in the frame in such manner that the same will be supported therein intermediate its ends, the heddle bar, with the heddles mounted thereon, is placed in the frame in the usual manner and its ends secured in position by means of whatever type of fastening device that may be used in connection therewith, the pivoted member 14 being in the open position as shown in Fig. 3 of the drawings. The central portion of the heddle bar is now inserted in the recess 13 of the extension 12 of the bracket member, and thereafter the pivoted member 14 is swung into the position shown in Fig. 2 of the drawings, permitting the latch-like end of the leaf spring 18 to engage the recess 17 in the end of said pivoted member 14. The member 14 will now be securely held in the closed position, confining the heddle supporting bar within the recess 13 of the extension 12 of the bracket member. When it is desired to remove the heddle supporting bar 8 from the supporting device, it will be necessary to manually lift the free end 20 of the leaf spring 18 from out of engagement with the recess 17 of the pivoted plate member 14, whereupon said plate member 14 may be swung to the open position to thereby permit the heddle supporting bar to be removed. It will be seen that there is thus provided a simple yet efficient means for supporting the heddle bars intermediate their ends which will prevent undue lateral movement of the heddle bars, and which is also so constructed and arranged as to prevent disarrangement of the parts of the supporting device itself. Possibility of the parts of the heddle frame, as well as of the supporting device itself, fouling on adjacent frames, during the reciprocation of the frames in

the loom, will thereby be reduced to a minimum.

Having thus described the nature and characteristic features of my invention, what I claim as new and desire to secure by Letters Patent is:

1. In a heddle frame, the means for supporting the heddle bars intermediate their ends comprising a device secured to the heddle frame bar, said device having an extension provided with a recess adapted to receive and support the heddle bar, said recess being open to one side of said extension, a member pivoted to said extension having a recess open to the opposite side from that of the recess in the extension and adapted to engage the heddle bar when the same is mounted in the supporting device, said pivoted member also having a recess in the end thereof, and a leaf spring adapted to engage the recess in the end of said pivoted member to lock the same in closed position. 75

2. In a heddle frame, the means for supporting the heddle bars intermediate their ends comprising a device secured to the heddle frame bar, said device having an extension provided with a recess adapted to receive and support the heddle bar, said recess being open to one side of said extension, a member pivoted to said extension having a recess open to the opposite side from that of the recess in the extension and adapted to engage the heddle bar when the same is mounted in the supporting device, said pivoted member also having a recess in the end thereof, and a leaf spring secured to the supporting member having its free end adapted to engage the recess in the end of said pivoted member to lock the same in closed position. 90

3. In a heddle frame, the means for supporting the heddle bars intermediate their ends comprising a bracket-like device secured to the inner edge of the heddle frame bar, said bracket-like device having an extension provided with a recess adapted to receive and support the heddle bar, said recess being open to one side of said extension, a member pivoted to said extension having a recess open to the opposite side from that of the recess in the extension and adapted to engage the heddle bar when the same is mounted in the supporting device, said pivoted member also having a recess in the end thereof, and a leaf spring secured to the bracket-like member having its free end adapted to engage the recess in the end of said pivoted member to lock the same in closed position. 95

4. In a heddle frame, the means for supporting the heddle bars intermediate their ends comprising a bracket-like device secured to the inner edge of the heddle frame bar, said bracket-like device having a rigid extension provided with a recess adapted to 100

receive and support the heddle bar, said recess being open to one side of said extension, a member pivoted to said extension beyond the recess therein and having a recess open to 5 the opposite side from that of the recess in the extension and adapted to engage the heddle bar when the same is mounted in the supporting device, said pivoted member also having a recess in the end thereof, and 10 means adapted to engage the recess in the end of said pivoted member to lock the same in closed position.

ber pivoted to said extension beyond the recess therein and having a recess open to the opposite side from that of the recess in the extension and adapted to engage the heddle bar when the same is mounted in the supporting device, said pivoted member also 45 having a recess in the end thereof, and a leaf spring secured to the bracket-like member having its free end passing through an aperture thereof and adapted to engage the recess in the end of said pivoted member 50 to lock the same in closed position.

5. In a heddle frame, the means for supporting the heddle bars intermediate their 15 ends comprising a bracket-like device secured to the inner edge of the heddle frame bar, said bracket-like device having an extension provided with a recess adapted to receive and support the heddle bar, said recess being 20 open to one side of said extension, a member pivoted to said extension beyond the recess therein and having a recess open to the opposite side from that of the recess in the extension and adapted to engage the heddle 25 bar when the same is mounted in the supporting device, said pivoted member also having a recess in the end thereof, and a leaf spring secured to the bracket-like member adapted to engage the recess in the 30 end of said pivoted member to lock the same in closed position.

6. In a heddle frame, the means for supporting the heddle bars intermediate their 35 ends comprising a bracket-like device secured to the inner edge of the heddle frame bar, said bracket-like device having an extension provided with a recess adapted to receive and support the heddle bar, said recess being open to one side of said extension, a mem-

7. In a heddle frame, the means for supporting the heddle bars intermediate their ends comprising a bracket-like device secured to the inner edge of the heddle frame bar, said bracket-like device having an extension provided with a recess adapted to receive and support the heddle bar, said recess being open to one side of said extension, a member pivoted to said extension beyond the recess therein and having a recess open to the opposite side from that of the recess in the extension and adapted to engage the heddle bar when the same is mounted in the supporting device, said pivoted member also 60 having a recess in the end thereof, and a leaf spring secured to the bracket-like member having its free end passing through an aperture thereof and adapted to engage the recess in the end of said pivoted member to 65 lock the same in a closed position, and said pivoted member having an inclined margin adjacent the end recess whereby said pivoted member may be swung into the locked position.

In testimony whereof, I have hereunto signed my name.

JACOB KAUFMANN.
